WRINGER ATTACHMENT

Benjamin F. Kalina, Bowman, N. Dak.

Application February 7, 1950, Serial No. 142,896

2 Claims. (Cl. 68—270)

1

This invention relates to an improved roller scraper attachment for a clothes wringer to prevent washed fabric from wrapping around the wringer rollers while being passed through the wringer.

It is among the objects of the invention to provide such an improved wringer attachment which can be quickly and easily mounted on an existing clothes wringer with no material modification of the wringer structure, which can be mounted with equal facility at either side of the wringer as may be desired, which is resiliently maintained in contact with the roller so that it will operatively engage a worn roller and can be moved away from the roller whenever necessary, which will fit various types of existing wringers, and which is simple and durable in construction, economical to manufacture, positive in operation, and fully effective to prevent washed fabric passed through the wringer from wrapping around the wringer roller to which the attachment is applied.

Other objects and advantages will become apparent from a consideration of the following description and the appended claims in conjunction with the accompanying drawing wherein:

Figure 1 is a rear elevational view of a clothes wringer with a roller scraper attachment illustrative of the invention operatively applied thereto;

Figure 2 is a transverse cross sectional view on the line 2—2 of Figure 1;

Figure 3 is a cross sectional view of a fragmentary portion of the assembly illustrated in Figures 1 and 2 and taken on the line 3—3 of Figure 2; and

Figure 4 is a cross sectional view on the line 4—4 of Figure 3.

With continued reference to the drawing, the clothes wringer illustrated is of conventional construction and comprises a frame having two spaced apart end portions 10 and 11, two juxtaposed, substantially parallel rollers 12 and 13 disposed between the frame end parts 10 and 11 and a sheet metal cover 14 extending over the upper ends of the frame parts 10 and 11 and the upper roller 13 and secured at its opposite ends to the frame parts.

Each of the rollers 12 and 13 comprises a metal shaft having a sleeve of resilient material, such as rubber, thereon. The roller 12 has a shaft 15 journaled at one end in the frame part 10 and at its opposite end in the frame part 11 and a sleeve or covering 16 of suitable resilient material, such as rubber, on the shaft between the two frame

parts. The roller 13 has a metal shaft 17 journaled at one end in the frame part 10 and at its opposite end in the frame part 11 and has a sleeve or covering 18 of resilient material, such as rubber on the shaft 17 between the two frame parts. Means are provided in one of the frame parts, for example, the wider part 11, to drive the two rollers 12 and 13 at the same speed in opposite directions so that laundered fabric, such as 19, will be carried between the two juxtaposed rollers and excess water will be forced from the fabric during the passage of the fabric between the rollers. The resilient coverings 16 and 18 provide for the passage of the thickened or doubled portions of the fabric, buttons and similar objects between the rollers without damage to the rollers or to the material or objects passing therebetween.

The cover 14 is a hollow sheet metal body having an open lower side, a top wall 20 at its opposite side and spaced apart, substantially parallel side walls 21 and 22 joined to the corresponding longitudinal edges of the top wall by arcuately curved portions, as indicated at 23. Each side wall has at its edge opposite the top wall 20 an inwardly turned flange 24, these flanges serving to reinforce and stiffen the side walls of the cover.

As the wringer may be of well known construction, a more detailed description is considered unnecessary for the purposes of the present invention.

The roller scraping attachment comprises, in general, a clamp assembly 25, a bracket 26 supported by the clamp assembly, and a blade 27 of flexible material carried by the bracket and engageable with the cylindrical surface of one of the rollers 12 or 13, preferably the upper roller 13 at the rear or outlet side of the wringer at a level below the horizontal center of the roller 13.

The clamp assembly includes a flat plate 28 having along one edge a hinge barrel 29 and having a deep notch 30 extending from the mid-length location of its opposite edge inwardly of the plate through the major part of the distance between the edge having the hinge barrel and the edge through which the notch extends, and a backing member 31 of hollow rectangular shape and including a flat planar portion and legs having free ends. The backing member 31 has a groove in one face thereof to receive the inwardly turned flange 24 of the cover, this groove being preferably provided in the free ends of the legs of the backing member having a longitudinally extending opening 32 therein, and the

backing member has an aperture in its flat planar portion. A screw 33 extends through the aperture in the back wall of the backing member 31 and through the notch 30 in the plate 28 and receives a wing nut 34 which bears against the outer side of the plate 28 to force the clamp assembly members 28 and 31 together with a portion of the cover 14 received therebetween to firmly clamp the attachment to the cover of the wringer.

The bracket 26 comprises two parts 35 and 36 of which the part 35 is a flat or second vertical plate of rectangular shape having hinge barrels 37 on one edge thereof and apertures intermediate its width. The hinge barrels 37 receive the hinge barrel 29 therebetween, and a hinge pin 38 extends through the hinge formations 29 and 37 to hingedly connect the bracket to the part 28 of the clamp assembly. The part 36 of the bracket is an elongated, sheet metal structure of L-shaped formation having two legs 40 and 41 disposed at right angles to each other. The leg 40 overlies a portion of the plate 35 and is provided with apertures which receive screws or rivets 42 by means of which the plate portion 35 is rigidly secured to the angular portion 36 of the bracket.

The material of the portion 36 of the bracket is doubled back over the inner surface of the leg 41 to provide a stiffening or reinforcing plate 43 and is doubled back again over the inner surface of the layer 43 to provide a blade retaining layer 44 which is parallel to and slightly spaced from the reinforcing layer 43, to provide a strip receiving space between the plates 43 and 44.

The blade 27 is an elongated strip of suitable, flexible material, such as rubber or leather, and is received in the blade receiving space between the bracket plates 43 and 44 and protrudes at one edge beyond the outer edge of the bracket leg 41 to engage the associated roller. The blade is firmly secured in the blade receiving space by deforming the plate 44 at spaced apart locations, as indicated at 45, by a suitable tool, such as a center punch.

A helical contractile spring 46 is secured at one end to the leg 40 of the bracket portion 36 at the inner side of such leg by suitable means, such as the screw 47 extending through a loop at the end of the spring and through a screw threaded aperture in the bracket leg and is secured at its opposite end to the clamp screw 35 at the side of the clamp assembly member 31 opposite the plate member 28 by suitable means, such as a loop or eye on the spring extending around the screw 33. This spring resiliently urges the bracket about its hinge connection with the clamp plate 28 in a direction to force the protruding edge of the blade 27 against the surface of the roller 13. The roller scraper attachment may be conveniently formed of sheet metal, such as light gauge sheet aluminum, except for the screw and nut, the spring and the blade of resilient material. This provides a durable and economical construction and the formation of the clamp assembly is such that the attachment can be mounted on various types of existing wringers.

The invention may be embodied in other specific forms without departing from the spirit

or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

10. What is claimed is:

1. In combination, a wringer comprising a pair of vertically superposed cooperating rollers, a cover above and coextensive with the upper one of the rollers, said cover having a vertical sidewall having a lower edge located at one side of the rollers, a vertical plate engaging a side of the cover sidewall and depending below the said lower edge of the sidewall in laterally spaced relation to the said one side of the upper roller, means securing said plate to the cover side wall, a second vertical plate having an upper end horizontally hinged to a lower part of said first named plate, an erect L-shaped bracket having two legs disposed at right angles to each other, one of said legs overlying a portion of and secured to said second vertical plate, said one leg normally occupying a vertical position with the other of said legs reaching laterally inwardly toward the said one side of said upper roller, a horizontal resilient blade mounted on and projecting beyond the laterally inward end of said other leg and engaging the said one side of said upper roller, and a contractile spring secured to and stretched between said L-shaped bracket and a portion of said securing means and yieldably urging said blade into engagement with said upper roller.

2. In a wringer roller scraper assembly, a blade for engaging a side of a wringer roller, means flexibly carrying the blade for movement toward and away from the roller, and clamp means for mounting said means on a part of the wringer, said clamp means comprising a plate for engaging one side of said wringer part, said plate being formed with a slot opening through one edge of said plate, a bolt extending through said slot and having a head on one end thereof, a rectangular shaped member having a flat planar portion and legs having free ends, said free ends being arranged to engage the inner side of said plate with said planar portion spaced from said plate, said planar portion being provided with a hole passing said bolt with the said head of the bolt engaging the side of the planar portion of said member remote from the legs of said member, and a nut on the bolt adapted to be turned in a direction to engage said nut with said plate so as to clamp said wringer part between said rectangular shaped member and said plate.
